(57) **CLAIM**

I claim the ornamental design for an animal hay feeder, as shown and described.

DESCRIPTION

FIG. 1 is a perspective view of an animal hay feeder, showing the new design with a bag thereof in a full configuration; FIG. 2 is a perspective exploded view thereof, the bag of the design in an empty configuration;

FIG. 3 is a front elevational view of FIG. 1;

FIG. 4 is a rear elevational view of FIG. 1;

FIG. 5 is a left-side elevational view of FIG. 1, the right-side elevational view being a mirror image thereof;

FIG. 6 is a top plan view of FIG. 1;

FIG. 7 is a bottom plan view of FIG. 1;

FIG. 8 is an exploded top plan view of a closure of the design, the bag omitted for clarity of illustration;

FIG. 9 is a left-side elevational view of FIG. 8, the right-side elevational view being a mirror image thereof; and,

FIG. 10 is a front elevational view of the closure, the rear elevational view being a mirror image thereof.

The broken lines showing a horse in FIG. 1 are included for the purpose of illustrating the invention in use, and form no part of the claimed design.
